UNITED STATES PATENT OFFICE

JOHN C. SCHELLENG, OF MILBURN, NEW JERSEY, ASSIGNOR TO WESTERN ELECTRIC COMPANY, INCORPORATED, OF NEW YORK, N. Y., A CORPORATION OF NEW YORK

SIGNALING SYSTEM

Application filed August 28, 1925. Serial No. 52,989.

This invention relates to signaling systems and more particularly to a three-phase directional transmission system.

In directional transmission systems heretofore proposed a common method of controlling the direction in which the waves are propagated is by means of a reflector. In one particular type of system, a parabolic reflector is used in the focus of which is placed the radiating member. This will effectively cut off the waves in one direction and will propagate a more or less parallel beam in the direction in which the reflector faces.

15 British Patent 226,246, June 21, 1923, discloses a system in which a multiple tuned antenna is used as a source of radiated waves. A second multiple tuned antenna, located a certain distance from and parallel to the first antenna, serves as a reflector to effectively neutralize waves radiated in one direction and to enable the system to be directive in the opposite direction.

In the above mentioned systems the current in the reflecting members is produced by the field radiated by the primary aerial. This current is less than the current in the primary aerial due to the resistance and other losses of the system, consequently complete neutralization does not occur.

To effect complete neutralization it is desirable to provide means for directly applying energy in proper phase relationship to the reflecting members to insure that the currents in the various aerials will be equal. A poly-phase power supply is well adapted to such a use as currents of the various phases may be applied to the different aerials to produce the desired result.

40 It is an object of this invention to provide for efficient directional radio transmission.

Another object is to provide for efficient directional transmission in a three phase system.

45 These objects and others which will be apparent as the nature of the invention is disclosed, are accomplished by employing in a directional transmission system, a multiple antenna system which is energized from a suitable source of poly-phase current. The

antenna system consists of a plurality of similar multiple-tuned aerials or linear antenna arrays arranged in parallel planes and separated from each other by a distance which is a simple fraction of the length of the wave it is desired to transmit. Each aerial is supplied with energy from one phase of the poly-phase high-frequency source.

55 In order to obtain a suitable source of poly-phase high-frequency modulated current, it is proposed to employ a poly-phase space discharge oscillator which is stabilized in operation by having impressed upon it a current of a frequency which is a harmonic of the frequency at which the oscillator is to operate. Current from the oscillator is impressed upon a harmonic generator which is adapted to produce current of the frequency desired for transmission. This high frequency current is amplified in a suitable poly-phase amplifier which also operates in accordance with this invention as a modulator, by means of which the poly-phase currents are modulated in accordance with low frequency signaling currents.

60 In order to make a complete disclosure of a particular system to which this invention may be applied a three phase system will be described in detail although other poly-phase systems may be employed if desired.

65 Although the novel features and combinations which are believed to be characteristic of this invention will be pointed out with particularity in the claims appended hereto, the invention itself as to its objects and advantages, the mode of its operation and the manner of its organization will be better understood by referring to the following description taken in connection with the accompanying drawings forming a part thereof in which

70 Fig. 1 shows diagrammatically a three-phase carrier current transmission system and

75 Fig. 2 shows a three-phase antenna structure adapted to be operated in connection with the system shown in Fig. 1.

80 Referring to the figures more in detail, in Fig. 1 is shown a three-phase space dis-

charge oscillator comprising space discharge devices 1 and their associated circuits. This system is similar to that shown and described in U. S. patent to Heising 1,690,226, 5 November 6, 1928. The three oscillators are maintained in proper phase relationship by means of condensers 2 interconnected in delta, each condenser being connected between the anodes of an individual 10 pair of the space discharge devices. Therefore, neglecting the stopping condensers which have relatively small impedances, a capacitative circuit may be traced from each anode to its corresponding cathode including 15 each of said condensers and the anode-cathode spaces of two of the devices. The capacity of this circuit is the frequency determining capacity of a tuned output type of oscillator. The corresponding inductive 20 path of the frequency determining circuit may be similarly traced through the anode coupling coil of each device although, to a limited extent and through certain of the condensers in series therewith, the coupling 25 coils of the other devices affect the frequency of each device. The frequencies of the several devices are made, as nearly as may be, equal. For a disclosure of the method of operation of a three-phase generating 30 system based on a similar principle reference may be made to above mentioned application of Heising.

The precise frequency at which oscillators including tubes 1 will generate oscillations 35 is controlled by a high frequency generator 3 which is so designed and constructed as to impress a wave of particularly stable frequency upon the input circuits of the various oscillator tubes to which it is coupled 40 by transformer 4, forming part of a tuned circuit 5.

The high frequency generator 3 may be of any form capable of generating an extremely stable frequency. One such system is shown in a copending application of 45 J. F. Farrington filed April 7, 1925, Serial No. 21,298 in which a comparatively low frequency oscillator, adapted to operate at a very constant frequency, is used to excite 50 a series of harmonic generators by means of which the frequency of the current produced by the first mentioned generator is stepped up to the desired value.

The manner in which a harmonic frequency 55 may be used to stabilize the frequency of an oscillator has been set forth and described in U. S. patent to Schelleng No. 1,527,228, February 24, 1925. In the system described in that patent, it is pointed 60 out that two oscillators, adapted to generate current at harmonically related frequencies, may be kept in step by impressing upon the input of the lower frequency oscillator waves of the harmonic frequency 65 generated by the other oscillator or a mul-

tiple thereof. A fundamental frequency wave could be used to stabilize the frequency of any one of the oscillator units, and therefore, through interaction between the units, to stabilize the frequency of the polyphase oscillator as a whole. However, in the present instance a harmonic of the same order as the number of phases, or an integral multiple thereof, is used, in order to symmetrically impress the maximum controlling effect on all of said oscillator units, and thereby insure optimum stabilization. Three phase oscillations generated by tubes 1 are impressed upon tubes 6 comprising a three-phase harmonic producer. The 70 output circuit of the harmonic producer includes tuned circuits 7 which are adapted to select a desired harmonic frequency. By this means a high frequency current is produced having a constancy of frequency determined by that of source 1.

Three-phase currents in the output circuits of tubes 6, which are harmonically related to the oscillations generated by tubes 1, are impressed by means of transformers 8, upon a three-phase amplifier consisting of space discharge devices 10. Since the process of harmonic production results at the same time in a like multiplying of the phase differences of the currents it follows 90 that the third harmonic currents and multiples thereof are in equal phase and are, therefore, unsuited for the purpose of the invention; the other harmonics, however, are properly phased. As herein shown by 100 way of illustration, a single space discharge tube for each phase is used, but any number of tubes may be connected in parallel to bring the amplifying capacity for each phase up to the desired value.

Spurious oscillations are prevented from occurring in the circuits of tubes 10 by means of balancing condensers 11 interconnecting the anodes and grids of the three tubes, whereby each grid is maintained at neutral potential with respect to the three plates and vice versa. The capacity of condensers 11 is substantially equal to the internal grid-plate capacity of the tubes.

The three-phase high-frequency high-power output wave of tubes 10 is modulated by signal frequency currents controlled by microphone 13 which is adapted to vary the space current flowing in tube 14 in the usual manner. Low-frequency choke-coil 15 prevents the production of speech frequency variations in the space current supplied by the source 16, due to the impressed signals from microphone 13. Inasmuch as space current is supplied to tubes 10 and 14 in parallel and variations in the current supplied by source 16 are prevented by choke coil 15, any increase or decrease in the amount of space current flowing in tube 14 must be compensated by a decrease or in-

crease in the current flowing in tubes 10 in the manner described in U. S. Patent 1,442,147, January 16, 1923 to R. A. Heising.

Modulated waves produced in the output circuit of tubes 10 are transmitted through 5 transformers 12 to the outgoing channel or transmission circuits 40, 41, and 42.

Grid polarizing potential is supplied to space discharge devices 1, 6 and 10 from 10 source 17 through potentiometers 18. High frequency choke coils 19 are adapted to prevent the high frequency oscillations from passing through source 17. Choke coils 20 in the anode circuits of the various tubes 15 prevent high frequency oscillations from being short-circuited through the source 16 of space current.

Three-phase modulated waves transmitted through transformers 12 are impressed upon 20 the aerial structure shown in Fig. 2, comprising multiple-tuned aerials A, B and C, placed in parallel planes and spaced apart. These aerials are spaced apart in a particular case by a distance approximately one- 25 third of the length of the wave it is desired to radiate, although the spacing may be varied to meet different local conditions. Aerials A, B and C are supported from towers or masts 21, 22 and 23, respectively, 30 and comprise vertical radiating members 24, each of which is tuned by an inductance 25, placed at the lower end thereof, and its capacity to ground, in such manner that the natural period of each of the members is 35 equal to that of the wave radiated. Vertical members 24 are suspended from member 26, connecting the towers, by supports including tension insulators 27. The supports are so adjusted in length that the upper ends of the radiating members 24 lie in the same horizontal plane. Each aerial has a horizontal length substantially greater than the length of the wave to be radiated.

Energy is supplied from the transmission 40 lines 40, 41 and 42 to aerials A, B and C by means of coils 28, 29 and 30 inductively coupled to coils 31, 32 and 33, respectively. The connection of the various coils is so chosen that each antenna structure is supplied with a modulated wave from one phase only of the source comprising tubes 10 and associated circuits. The operation 50 of the antenna system would not be materially changed, and not at all in principle, if the various radiating members 24 constituted separate and individual aerials, the combination including all of such aerials corresponding to each multiple-tuned antenna disclosed, each of such aerials having 55 impressed on it through an individual transformer a wave from an individual one of transmission lines 40, 41 or 42.

The radiating system operates as follows:

The separate transmission lines, 40, 41 and 60 42 are connected to the secondaries of trans-

formers 12, and the numbers 40, 41 and 42 represent the order in which the corresponding voltages across these secondaries attain a given phase, that is, the numbers represent the order in which these voltages 70 have a maximum value, assuming that the coupling between the transmission line and the antenna is such that no reflection occurs from the antenna end of the transmission line.

Waves impressed by transformers 12 on the line, travel to the right along the transmission line with a velocity substantially equal to the velocity of a wave in free space. Referring the phases of the currents in lines 41 and 42 to that in line 40 as standard, the current in line 41 lags one-third of a period and current in line 42 lags two-thirds of a period behind that in line 40. The longer transmission lines 41 and 42 add a further 80 lag of one-third period and two-thirds period, respectively, so that currents in antennæ B and C lag behind that in antenna A by two-thirds period and four-thirds period, respectively. Since a lag of four-thirds period is the same as a lag of one-third period in respect to interference effects produced in space, the antennæ have their maxima of current in the order ABC 90 which is the same as CBA. This is the reverse of the order at transformers 12, the reason being that different times are required for the wire wave to travel to the antennæ.

It follows that no signal will be transmitted toward the right, for since the velocity of the wave along the wires is substantially the same as that of the wave radiated the same time is required in the three channels for the effect of a wave to 100 reach a given point to the right, and since at transformer 12 the total current in the three lines is zero, the effect at points to the right is also zero. On the other hand, currents in antennæ C, B and A reach a 110 maximum in the order which is needed for these effects to add at a distant point to the left. A wave from antenna C needs an earlier start than one from antenna B for the maximum of the two radiated waves to 115 reach the distant point at the same time. Since distance between antennæ B and C equals one-third of a wave-length the phase difference of one-third of a period which has been shown to exist between antennæ 120 A and C is just what is needed.

For directions perpendicular to the plane of the paper the effect of resultant field strength of the antennæ is zero, since the distances to the antennæ are the same from a distant point, and the currents of the three antennæ are in three-phase relationship.

Effects produced by any differences between the velocity along the transmission lines 130

and the velocity of a wave in space may be eliminated by altering the length of the transmission lines in such a manner that the antenna currents are in the proper phases.

If the order of the phases of the currents in transmission lines 40, 41 and 42, or the order of the connections from such transmission lines to the antennæ is reversed it is seen that the currents in all of the antennæ will be in the same phase, which is a condition for maximum signal in a direction perpendicular to the paper and zero transmission to the left or to the right. In this case it is not desirable to employ long multiple tuned antennæ A, B and C, the proper length being small compared to a wavelength.

If the power station is connected to the three antennæ by lines of equal length the antenna arrangement shown is also unidirectional and the directions can be reversed by reversing the order of the phases as before.

With certain forms or sizes of antenna the antenna currents might differ in size or phase from those in the case described above due to the interaction which exists between the currents of the various antennæ. This effect may be compensated for by suitable selection of spacing, tuning or phase relationship. Since a three-phase source of supply is available it is possible to employ a large variety of phase relationships.

The purpose of using multiple-tuned antenna units or of parallel antenna arrays may be explained as follows: From one point of view the antenna system may be thought of as comprising as many sets of directive antenna systems, each comprising three vertical spaced aerials, as there are radiating members 24 in each of the multiple-tuned antennæ disclosed or, considered more broadly, of as many such systems as there are individual antennæ in each of antenna arrays 21, 22 and 23. These sets of directive systems superpose their effects. This indicates the desirability of using multiple-tuned antennæ having a large number of radiating members 24. From another point of view, and for the purpose of indicating the desirability of making each multiple-tuned antenna long as compared with the length of the wave to be radiated, each of the multiple-tuned antennæ may be thought of as a directive antenna array whose purpose is to insure substantially zero radiation in either direction along its axis and a maximum radiation in directions at direct angles thereto. These desired directive properties, as is well-known, require that the array be long as compared with the wave length of the radiated waves. The fact of directivity of such arrays would be clearly apparent if the radiating members 24 were a half wave length or a multiple

thereof apart. The conditions are not changed by the use of a greater number of such members spaced a lesser distance since the array may be resolved into a plurality of such elemental arrays having the half-wave spacing. The considerations above expressed indicate the advantage of using both a large number of radiating members 24 and of using relatively long multiple-tuned antennæ comprising such members.

An advantage of the system described, is that power is supplied equally to the various aerials to insure equal radiation and increase the directive properties. The directional effect may be still further increased by employing additional aerial structures and supplying them with currents in the proper phase relationship. The use of a poly-phase current generator provides means for energizing the aerials with currents in any desired phase relationship to obtain the proper directional effect without necessitating the use of phase shifting networks and filters.

The three-phase system, such as shown in Fig. 1, avoids the connection of a plurality of space discharge devices in parallel; so that the tendency of the device to generate certain spurious oscillations is greatly decreased.

Although this invention has been shown and described as applied to a particular system, it should be understood that it is not to be limited thereto, but only in accordance with the scope of the invention as defined by the following claims.

What is claimed is:

1. In a transmission system including a plurality of multiple-tuned aerials in parallel planes and a source of polyphase currents, means for energizing each aerial with single phase current from such source in such manner that the currents in the various aerials are in different phase relationship.

2. A polyphase transmitting antenna structure comprising a source of polyphase current and a plurality of aerials connected therewith, corresponding in number to the number of phases, each comprising a linear array of substantially parallel antenna units, each tuned to the frequency of said current and connected in parallel, the planes occupied by such arrays also being in parallel with each other.

3. A directive three-phase transmitting antenna system comprising a plurality of multiple-tuned aerials in parallel planes and spaced apart by a distance approximately one-third of the length of the wave to be radiated.

4. A directive polyphase transmitting antenna system comprising a plurality of multiple-tuned aerials in parallel planes, each of said aerials having a horizontal

- length substantially greater than the length of the wave to be radiated therefrom.
5. In a transmission system, a source of modulated polyphase currents, and a poly-⁵ phase antenna structure having multiple-tuned aerials for radiating waves due to said currents.
6. In a transmission system, a source of high frequency polyphase oscillations modu-¹⁰ lated in accordance with a low frequency signaling wave, in combination with a polyphase antenna structure comprising a plurality of multiple-tuned aerials.
7. In a signaling system, a source of polyphase oscillations, means for producing polyphase oscillations harmonically related thereto, and means for modulating said last mentioned oscillations in accordance with a low frequency signaling wave, in com-²⁰ bination with a polyphase antenna structure.
8. In a signal transmission system, a source of polyphase oscillations, means for producing polyphase oscillations harmonically related thereto, means for amplifying said last mentioned oscillations, and means for modulating said last mentioned oscillations in accordance with a low frequency signaling wave, in combination with a poly-³⁰ phase antenna structure, and means for impressing said modulated oscillations upon said antenna structure.
9. In a signal transmission system, a source of polyphase current comprising a plurality of space discharge oscillators having input and output circuits, means for producing oscillations harmonically related to said current, the order of the harmonic being equal to the number of phases of the current from said source or a multiple there-³⁵ of, and means for impressing said oscillations upon the input circuits of said space discharge oscillators whereby the frequency of said polyphase currents is controlled, a harmonic producer comprising discharge devices for producing polyphase currents harmonically related to said first mentioned currents, a polyphase amplifier for amplifying said last mentioned currents comprising
- 40 space discharge devices having anodes, cathodes and control elements, condensers connected between anode and control elements of said devices whereby the tendency to produce spurious oscillations is minimized, a source of signaling current, means for impressing said signaling currents upon the anode circuit of of said amplifier whereby a modulated polyphase current is produced, a polyphase antenna structure, and means
- 50 for impressing said modulated currents thereon, said antenna comprising a plurality of aerials, spaced apart a distance equal to approximately one-third the length of the wave to be radiated divided by the number
- 55 of phases.
10. A communication system comprising a source of modulated polyphase currents, a polyphase antenna system, and means for supplying energy derived from said currents to said antenna system, each antenna of said system comprising a linear array of unit antennæ extending in a direction substantially normal to the direction of extension of the antenna system as a whole.
11. A communication system comprising a source of modulated three-phase currents, three directive antenna arrays together comprising a three-phase antenna system, and means for supplying energy derived from said currents to said antenna arrays.
12. In a system of communication including a plurality of antenna arrays, a method of transmission which comprises generating a polyphase current, modulating said current in accordance with signals, and transmitting modulated current of different phase to the respective antenna arrays.
13. In a system of communication includ-⁸⁵ ing three antenna arrays, a method of transmission which comprises generating a three-phase current, modulating said current in accordance with signals, and supplying modulated current of a different phase to the respective antenna arrays.
14. A radio transmission system comprising a space discharge polyphase current source, a plurality of aerials equal in number to the number of phases, and means for energizing each aerial with a single phase current from said source in such manner that the currents in the various aerials are in different phase relationship, said aerials being spaced a distance equal approximately to the length of the wave to be radiated divided by the number of phases.
15. An oscillation generating system comprising a plurality of space discharge unit oscillators, means actuating said unit oscillators to maintain them in synchronism and in a symmetrically parallel phase relation, means for producing oscillations harmonically related to the oscillations generated by said unit oscillators, the order of the harmonic being the same as the number of phases of the oscillations generated by said oscillators or a multiple thereof, and means for impressing the oscillations from such harmonic oscillator on the input circuits of said unit oscillators, whereby the frequency of the resultant polyphase oscillator is controlled by the frequency of the oscillations from such harmonic oscillator.
- In witness whereof, I hereunto subscribe my name this 27th day of August A. D., 1925.
- JOHN C. SCHELLENG.
